UNITED STATES PATENT OFFICE.

RUSSEL G. WOODWARD, OF WAUKEGAN, ILLINOIS, ASSIGNOR TO UNION SPECIAL SEWING MACHINE COMPANY, OF CHICAGO, ILLINOIS, A CORPORATION OF ILLINOIS.

LOOPER-THREAD PULL-OFF FOR SEWING-MACHINES.

No. 908,839.

Specification of Letters Patent.

Patented Jan. 12, 1909.

Original application filed February 18, 1902, Serial No. 94,599. Divided and this application filed April 17, 1902. Serial No. 103,323. Renewed March 11, 1908. Serial No. 420,447.

To all whom it may concern:

Be it known that I, RUSSEL G. WOODWARD, a citizen of the United States, residing at Waukegan, in the county of Lake, State of Illinois, have invented certain new and useful Improvements in Looper-Thread Pull-Offs for Sewing-Machines, of which the following is a description, reference being had to the accompanying drawing and to the letters and figures of reference marked thereon.

This application is a division of my application filed February 18th, 1902, Serial No. 94,599, for improvements in overseaming sewing mechanism, and pull off devices therefor.

Primarily, the invention includes a novel construction of adjusting devices for the looper thread pull off, as hereinafter described and referred to in the appended claims.

In the accompanying drawings, which illustrate the invention, Figure 1 is a top plan view, partly in section, of so much of the Union Special interlock sewing machine, as is necessary to a complete understanding of my invention; Fig. 2 is a detail side elevation, partly in section, of the mechanism for adjusting the looper thread eyelets; Fig. 3 is a detail of the connection between the eyelets and the adjusting rod; and Fig. 4 is a skeletonized view, showing the looper operating mechanism. Fig. 5 is an enlarged rear perspective view, illustrating the mechanism for swinging the pivoted cast off plate and adjusting the looper eyelets; Fig. 6 is a detached view showing the connection between the adjusting rod, the eyelets and the means for holding the eyelet support in place.

The shape of the machine is of the well known Union Special type, and it is not necessary to herein refer to the parts specifically, except to say that N is the needle; L the looper; and S the spreader or looping hook, the parts being so constructed and operating that the loop thrown out by the needle loop below the work plate is seized by the spreader or looping hook S, and carried above the work plate to a point where the looper L in its oscillatory movement passes into it and carries its own thread into position to be engaged by the needle in its next descent. The looper L is attached to an

oscillating shaft M, and has suitably connected with its upper end, so as to oscillate with it an arm coöperating with thread-guiding arms, whereby the needle thread is properly manipulated, but it is not necessary to refer particularly to these parts.

In general, the looper thread pull-off is similar to that shown in the patent granted to Lansing Onderdonk and myself, November 27th, 1908, Number 837,106, and comprises the movable fingers or arms 7, having shoulders 8, extending between eyelets 9 on the frame of the machine, through which eyelets the looper thread is guided. In a plane between these fingers or arms is a pivoted cast-off plate 11, which at one time or another, according to its position, acts to force the thread off the shoulders 8 on the movable finger 7. The cast off plate 11 is provided with a forked extension 11^a which engages a pin 11^b carried by an arm on the lever for shifting the needle as shown and described more fully in my Patent #837,255, granted November 27th, 1906.

As a further improvement in machines of this character, the pull-off for the looper thread is made adjustable by adjusting the arms R, carrying the eyelets 9. These arms are formed on a common support n, which is adjusted back and forth by the screw-threaded rod U, having on one end the thumb piece k, and screw-threaded through a part of the goose-neck of the machine, and at its other end attached to the support for the arms R. This support fits in a depression on the goose-neck of the machine, being slotted at z, and having the external plate y secured to the goose-neck by the screw z, which passes through the slot, the plate y having upper and lower flanges to embrace the upper and lower edges of the support n. By this arrangement, the operator may regulate the amount of looper thread required, when thickness of goods or tightness of stitch, varies, and this can be done without stopping the machine, by merely turning the screw rod U. It will be understood that this feature of the operator's being able to regulate the amount of looper thread without stopping the machine is of great practical importance in a machine of this character. For example, very frequently an operator will have a number of different kinds or lots of goods brought to her, of varying weight

or thickness, and by this arrangement she can run from one kind or lot to another, without stopping the machine, and regulate the supply of thread for the looper to give 5 the proper elasticity to the stitch, by simply turning the screw rod U in one direction or the other.

Having thus described my invention, what I claim as new, and desire to secure by Letters Patent, is:—

- 10 1. In a sewing machine, a pull-off device for the looper thread, comprising a plurality of thread guides mounted on an adjustable support, a thread pull-off member engaging the thread between the said eyelets, and a pivoted cast-off plate located in the path of said pull-off member and means for adjusting said cast-off plate on its pivot; substantially as described.
- 15 2. In a sewing machine, a pull-off device for the looper thread, comprising a pull-off member, a cast-off, and thread guides arranged upon opposite sides of the pull-off member, a support therefor mounted upon the machine frame, and means for adjusting the latter, comprising a rod screw-threaded upon the machine frame and attached at one end to the thread guide support; substantially as described.
- 20 3. In a sewing machine, a pull off device for the looper thread including a pull off member and thread guides, and means for positively changing the relative arrangement of the thread guides and pull off member operative while the machine is in motion, and a cast-off plate.
- 25 4. In a sewing machine, a pull-off device for the looper thread comprising a pull-off member, thread guides upon opposite sides thereof, and means operative while the machine is in operation for simultaneously moving the thread guides positively to adjust the same; substantially as described.

5. In a sewing machine, a pull-off device for the looper thread, comprising a pull-off member, a cast-off, and thread guides upon opposite sides of the pull-off member, a support for said thread guides and means for adjusting the support and means for adjusting the cast off; substantially as described.

6. In a sewing machine, a pull-off device for the looper thread, comprising a pull-off member, a cast-off, and thread guides arranged upon opposite sides of the pull-off member, said thread guides being mounted on a common support, said support being attached to the goose-neck of the machine, and a plate having upper and lower flanges embracing the upper and lower edges of the support, said plate being secured to said support, and a screw-threaded rod for adjusting the support; substantially as described.

7. In a sewing machine, a pull-off device, comprising a pull-off member, a cast-off, and thread guides arranged upon opposite sides of the pull-off member, a support for the thread guides, said support including a slotted plate attached to the machine frame, with means for holding it in suitable guiding ways, and means for adjusting said support; substantially as described.

8. In a sewing machine, a pull-off, including stationary eyelets, a movable member reciprocating in a plane between the same and a cast-off plate or cam arranged to cast off the thread from said movable member, and means for adjusting the position of the cast-off.

In testimony whereof I affix my signature, in presence of two witnesses.

RUSSEL G. WOODWARD.
